CONTROL PANEL FOR A TELEVISION RECEIVER

Rudolph W. Krolopp, Villa Park, and Edwin O. Stastny,
Lombard, Ill., assignors to Motorola, Inc., Chicago,
Ill., a corporation of Illinois

Filed Oct. 14, 1960, Ser. No. 62,490

Term of patent 14 years

(Cl. D56—4)

Fig. 1.

FIGURE 1 is a perspective view of a control panel for a television receiver showing our new design;

FIGURE 2 is an enlarged top plan view; and

FIGURE 3 is a further enlarged side elevational view thereof.

The broken line showing of a portion of a television receiver and antenna is for illustrative purpose only.

We claim:

The ornamental design for a control panel for a television receiver, as shown and described.
